MULTI-BREAK ELECTRIC SWITCH

George W. O'Keeffe, Milton, Mass., assignor to
Condit Electrical Manufacturing Corporation,
South Boston, Mass., a corporation of Massa-
chusetts

Application January 24, 1929, Serial No. 334,783

16 Claims. (CL 200—16)

This invention relates to electric switches which are especially adapted to control the circuits of multi-phase motors up to say fifteen horse power at around six hundred volts, although not limited to such use.

In a copending application of Chester D. Ainsworth, Serial No. 322,730, filed November 30, 1928, assigned to the assignee of this application, there is disclosed and claimed a switch that is characterized by having four serially-connected points of circuit interruption in each phase conductor and so arranged and constructed as to eliminate the circuit interrupting arcs that heretofore have invariably been formed when the switch has opened under load.

It is an object of the present invention to provide a switch embodying the principles of the switch of said application.

A further object of the invention is to provide a multi-break switch wherein the stationary and movable contact members are carried by horizontal relatively movable supporting plates and operating mechanism to move the movable plate between switch open and switch closed position while maintaining it in a horizontal position.

Another object of the invention is to provide a switch wherein the movable contact members are supported on a supporting plate carried removably in a movable frame.

A further object is the provision of means for locking the removable supporting plate for the movable contact members so that it cannot be removed from operative position when the switch is closed.

Another object of the invention is the provision of a switch which is so designed that the separate parts thereof can be removed either with the fingers alone or by the use of such simple tools as a screw driver or pliers, so that they can be inspected, adjusted and repaired readily and also so that the various parts of the switch can be assembled rapidly by inexperienced labor.

In a switch adapted for motor control service, it has been found that a workman, in connecting the switch with its circuits, will position the conductors improperly in the enclosing casing, so that they are liable to foul the operating mechanism and prevent the proper operation of the switch.

It is a further object of the present invention to provide guard members which are so positioned within the enclosing casing as to obstruct such passages therein that are not adapted to have conductors extended therethrough.

A further object of the invention is an arrange-

ment of stationary and movable contact members such that the movable contact members are free from flexible leads or other conductors. To this end, an odd number, as three, insulated, stationary contact members and an even number, as two, insulated movable contact members are provided for each power circuit through the switch. Thus the end stationary contact members can be connected respectively with the incoming and outgoing circuit leads and the movable contact members can be free from direct connection with any leads.

A further object of the invention is generally to improve the construction and operation of electric switches.

Fig. 1 is a side elevation of an electric switch embodying the present invention, the enclosing casing being shown in section.

Fig. 2 is a front elevation of the switch of Fig. 1, the cover of the enclosing casing being broken out.

Fig. 3 is a sectional elevation taken along line 3—3 of Fig. 2.

Fig. 4 is a side elevation of the switch of Fig. 2 with the casing and the relay base removed to illustrate more particularly the arrangement of the closing electromagnet and the operating mechanism.

Fig. 5 is a plan view of the switch.

Fig. 6 is a section taken along line 6—6 of Fig. 30 with the movable contact carrier in a partially withdrawn position.

Fig. 18 is a perspective view of the movable holding frame for the movable contact carrier.

Fig. 19 is a perspective detail taken partly in section through one of the side plates to illustrate the construction of one of the operating mechanisms and its relation with a side plate.

The switch here shown is contained within the enclosing casing having the fixed back part 20 and the front part 22 which is hinged to and constitutes a cover for the back part. The two parts of the casing are latched in closed relation and by the latch 24, see Fig. 2. An attaching bracket 26, see especially Fig. 16, is secured, as welded, to the inner face of the rear wall of the part 20 of the casing and has forwardly extended and oppositely reflexed flanges 28 on which the switch is adapted to be secured. Said flanges carry attaching screws 30 that are screw threaded therein and have their inner ends peened over so that they can not be removed readily from the flanges. The bracket also has a forwardly extended plate 32 which is located between said flanges and is adapted to be disposed behind the operating mechanism of the switch. Said flanges 28 are spaced from the back wall of the casing and terminate close to the side walls thereof, as illustrated clearly in Fig. 5, and cooperate with the casing to provide vertical ducts 29 for the circuit conductors located at the sides of the casing away from the movable parts of the switch. The forwardly extended plates 32 constitute a barrier which obstructs the vertical passage between the back of the switch and the back wall of the casing and thus prevents the circuit conductors from being extended therethrough which, if they were so extended, might foul the operating mechanism and so prevent the proper operation of the switch.

The switch includes the left and right hand side plates 34 and 36 respectively, see particularly Figs. 2, 4 and 17. Said plates are provided with pairs of inwardly directed reflexed ears 38 upon which the stationary contact carrier 40 rests and to which it is secured rigidly by the screws 42. Said plates 34 and 36 are provided near the bottoms thereof with inwardly reflexed ears 44 which have intermediate portions 44a that are parallel with said plates and have inwardly directed parallel end portions 44b that lie near but on one side of the material median lines of said plates. The horizontally-extended M-shaped core 46 of the operating and holding electro-magnet is located upon the similar faces of said end portions 44b, so as to be in the median lines of said plates and is riveted fixedly to said end portions by the rivets 47. Said core and said carrier 40 constitute the means which secures said side plates rigidly in spaced relation, no other means being necessary. Said side plates are also formed at the bottom rear edges thereof with outwardly reflexed flanges 48 which are adapted to bear upon the flanges 28 of the supporting bracket 30. Said flanges 48 have vertically elongated slots 50 therein which communicate at their lower ends with enlarged circular openings 52 through which the heads of the holding screws 30 can be passed so that the bodies of said screws can enter said slots 50. The arrangement is such that by backing off said screws 30 and by raising the switch and thereupon by pulling it forwardly, the switch can be removed from its connection with said supporting bracket.

The stationary contact carrier 40 consists of a rigid rectangular plate of some suitable insulating material such as bakelite, or some other material capable of being molded into shape. Said carrier is provided on its under face with

three sets of stationary insulated contact members 54, 54a, 54b arranged in spaced relation in a line extended from the front to the rear of said plate. Three of such lines of contact members are herein provided, one for each phase circuit through the switch and said lines are arranged in spaced relation across said plate. All of said stationary contact members are identical and interchangeable. Each contact member, see especially Fig. 8, consists of a thick elongated copper bar or plate at the end and on the under faces of which are provided spheroidally shaped bosses or contacts 56 formed by expressing the material of the bar, and thus providing correspondingly shaped recesses 58, in the under face of said bar. Said bar between said recesses is provided with an internally screw-threaded passage 60 in which an attaching bolt 62, which is passed through the insulating plate 40, is removably screw-threaded whereby to secure each contact member separately to said insulating plate.

The stationary contact members of the sets are received in parallel grooves 64 formed in the underside of said carrier-plate whereby the contact members are held against lateral or rotary movements and thus are maintained permanently in alignment.

The end contact members 54 and 54b are adapted to be connected to the conductors of the power circuits. To this end, a terminal plate 66 is received in the ends of each of said slots 64 under the contact members 54 and 54b. Said plates have upstanding ears 68 which overlie the front and rear sides of said carrier-plate and are provided with attaching screws 70 for the circuit leads. Each of the plates 66 is secured to the carrier plate by a screw 72. Each plate is thus secured independently of the securing means for the contact members which consequently can be removed for inspection without disturbing said terminal plates or their connections with the conductors. The intermediate contact members 54a are secured in said slots 64 each by an attaching screw 74. Connectors 76 are also clamped to said carrier plate by said screw and provide terminals to which the control circuits for the operating electro-magnet are connected. An upstanding ledge 78 of said carrier plate provides a barrier between the screws 62 and the terminals and also constitutes means to hold said terminals against rotation. The plate is also provided with depending barriers 80 which are located on opposite sides of and between the sets of stationary contact members and also in front and in the rear of the end contact members of said sets for the purpose of preventing intermingling of the arc gases of the various phases when the switch is opened upon overload or on voltages far in excess of the load and voltage for which the switch is designed. The design of the switch is such that when it is operated on such voltages that the voltage across any point of circuit interruption is less than approximately two hundred volts and where the current is such that the contacts 56 do not become heated to an ionizing temperature during the first half cycle of current flow, the circuit is caused to be interrupted completely at the end of the first half cycle of current flow without the formation of the usual arcs. Consequently, when the switch is operated on circuits for which it is designed, these barriers are unnecessary.

The movable contact members 84 are carried

by a carrier 82 which comprises a rectangular plate formed of insulating material and similar in its composition to that of the stationary contact carrier 40. Said carrier 82 is provided with three horizontally spaced sets of contact members each set of which consists of two spaced contact members 84. All of said contact members are identical and interchangeable and are similar in construction with the stationary contact members 84 and have similarly formed contact bosses 86 at their opposite ends and a recess 88 between said bosses. Said movable contact members are located beneath the stationary contact members and in position each to engage an inner boss of the outer contact members 84 and 84b and a separate boss of the common inner contact members 84a, thus to control the circuit between said contact members 84 and 84b and to provide four points of circuit interruption in series for each phase conductor.

Each movable contact member is supported resiliently and removably by said carrier plate 82. To this end, see especially Figs. 3, 6 and 7, the carrier is provided under each contact member with a rectangular depression 90 in its upper face in which channel shaped brackets 92 are seated. The legs 92a of said channels extend above said carrier-plate and overlie the opposite sides of said contact members and have their upper ends reflexed inwardly to provide opposed horizontal ears or abutments 94 against which the upper faces of the movable contact members between the bosses thereof are pressed yieldingly and removably.

The contact members are each supported on the enlarged flange 96 of a supporting pin 98 which is slidably extended vertically through an opening in the carrier at the bottom of the recess and has a reduced upper end 100 that is located removably in the aperture 98 in the contact member and constitutes a fulcrum therefor about which the contact member can tilt to align itself with the cooperating stationary contact members. A compression spring 102 encircles the pin 98 and bears against the bottom member 82b, channel member 92 and also against the flange 96 of said pin whereby to hold the contact member yieldingly against the reflexed ears 94 of the channel member, and also to hold said channel member in its recess in said carrier. The bottom end of said pin is provided with a button 104, under said carrier, which is adapted to be grasped between the fingers and pulled downwardly whereby to compress the spring 102 and to withdraw the pin from its engagement with the contact member, thus permitting the contact member to be removed from the carrier. The button 104 also serves to limit the upward movement of the pin when the contact member is removed, thereby to prevent the disengagement of the parts.

Barriers 106 are extended from front to rear of said carrier 82 between said sets of movable contact members but are unnecessary except under conditions that render the barriers 88 necessary.

The movable contact members and the supporting structure therefor are described and claimed in my divisional application filed February 20, 1929, Serial No. 341,519, now Patent No. 1,895,767.

The carrier 82 is removably supported in a holding frame that is movable vertically to open and close the switch. Said holding frame, see especially Fig. 18, consists of a horizontal metal

plate 108 having upwardly reflexed and parallel end walls 110 and inwardly turned horizontal edges 112 which constitute tracks that support the movable carrier 82. Said carrier is provided with parallel guide slots 114 in its opposite end faces in which said tracks 112 are loosely received. The forward edge of said carrier is provided with a handle 116, see especially Fig. 6, by which the carrier, with its contact members, can be withdrawn from the track and removed entirely from the switch. A leaf spring 118 is fixed at one end to the plate 108 and has an upwardly directed projection 120 that is adapted to spring into a notch 122, see Figs. 3 and 7, of the movable carrier whereby to hold the carrier releasably in operative position. The carrier frame has a pair of inwardly-directed projections 113 at the rear thereof which are adapted to be abutted against by the removable contact-supporting carrier 82, whereby to limit the horizontal movement of the carrier and define the operative location thereof. The horizontal position of the metal plate 108 is provided with an aperture 116 therein below the buttons 104 of the contact-supporting pins 98 so that said buttons can enter said aperture in their depressed switch-closed positions without engaging the carrier frame.

An important feature of this construction by which the movable contact carrier 82 can be withdrawn and inserted in an inverted position in the holding frame, whereby to provide an effective lock out for the switch, is described and claimed in my continuing application Serial No. 509,726, filed January 17, 1931, now Patent No. 1,845,514.

The movable carrier plate 82 is prevented from being withdrawn from the switch when the switch is closed. To this end, the side plates 34 and 36 are provided with reflected inwardly-directed ears 121 which overlie the path of movement of the carrier plate and enter opposed notches 123 formed in the upper face thereof when the plate is in switch closed position, whereby to lock the plate against horizontal movement. When the plate is in switch-open position, however, it is free from holding engagement with said ears and so is free to be withdrawn from the switch.

Said carrier frame is guided for vertical movement by and between the side plates 34 and 36. Said side plates are provided with pairs of inwardly directed parallel ears 124 at both their front and rear edges, see especially Fig. 17, which are loosely received in spaced vertical slots 126 formed in the upstanding side walls 110 of said frame. The frame is thus guided for vertical movement in parallel lines by said ears and also is prevented from undue lateral movement by the engagement of said ears with the bottoms of said slots 126.

Said frame is reciprocated by operating mechanism that is duplicated at each end of the frame. The bottom plate 108 of the frame, at each side, is provided with downwardly reflexed ears 128. Each of said ears is pivotally connected to the upper end of a vertical link 130, see especially Fig. 19, the lower end of which is pivoted to the horizontal leg 132 of a bell crank lever 134. Said bell crank lever is pivoted on a pin 136 carried by a side plate at the rear of the vertical median line thereof and is spaced therefrom by a spacing member 138. The vertically extended leg 140 of said bell crank lever is pivoted by a pin 142 to one end of a toggle link 144. The free end of said link is pivoted to the reduced end 146 of a pin 148 which pin has an enlarged section 150 that extends loosely through a vertically extended arm 75

152 of an armature-supporting frame. Each of said side plates 34 and 36 is provided with inwardly struck out parallel ears 154 which have inwardly directed ends 156 that are spaced from each other and provide parallel vertical confronting faces 157 and a vertical slot 158 therebetween. The enlarged section 156 of said pin 148 is vertically movable in said slot 158 to guide the end of said link 144 for vertical movement in a straight line; and the pin is adapted to bear against said confronting faces in switch closing and opening movements. Each of said arms 152 is received on its pin between said reflexed ears and the link 144 and operates in the space between said reflexed ears 156 and the body of the side plate. Said side plate is also provided with a set of inwardly directed struck out parallel ears 160 which are located below and in parallel relation with the ears 154 and constitute additional guiding means for the vertical movement of the arms 152. The arrangement of the mechanism is such that the links 144 are straightened and move almost into horizontal positions, or normal to said faces 157, when the arms 152 are raised whereby to raise the movable contact members into pressure applying engagement with the cooperating stationary switch members. The links 144 cooperate with the pins 148 and the vertical slots 158 to form abutment-toggles by which the operating force that actuate the arms 152 is enhanced at the co-operating contact members.

Said arms 152 are connected integrally at the lower ends thereof by a horizontal plate 162, see especially Figs. 4, 12 and 13, on which the bar-shaped armature 164 for the actuating electromagnet 46 is received. Said armature is provided with opposed side plates 166 that extend beyond the ends of the armature and overlie the angularly-inclined lower ends 165 of said arms 152 whereby to hold the armature from undue lateral movement on said holding frame. Said holding frame is provided with integral struck out ears 168 which provide passages under them through which, and through passages in said end plates 166, removable retaining pins 170, here shown as cotter pins, are received. By means of said pins, said armature is connected loosely with said frame whereby it can align itself with the poles of said magnet core 46 and prevent undue noises when the magnet is energized. Said pins can also be removed readily from the front of the enclosing casing whereby to remove said armature from its holding frame upon need. The magnet core 46 is provided with an energizing winding or coil 172 which is adapted to be energized to raise the armature holding frame and close the switch and to remain energized for so long as the switch is closed.

A guard plate 174 is disposed beneath said armature holding frame and has an upturned front edge 176 located in front of said armature and extends rearwardly beyond said armature and is terminated adjacent the rear wall of the fixed part 20 of the enclosing casing. Said plate has upstanding side arms 178 which overlie the side plates 34 and 36. The upper ends of said arms 178 are provided with slots 180 therein which are open at the tops and in which attaching screws 182 carried by said side plates are received, whereby to secure said plate removably in the position illustrated. The upper ends of said arms are outwardly reflexed to provide ears 184 on opposite sides of said slots 180, which ears are adapted to engage the heads of said screws thus to support the plate against down-ward movement when the screws are screwed down. Said screws 182 are permanently secured in said side plates by heading over the inner ends thereof but can be backed out enough to permit the ears 184 to pass between the heads of said screws and said side plates. Said upstanding arms 178 are provided with inwardly-directed upwardly-inclined projections 186 which are adapted to enter slots 188 of said side plates and bear against the inclined faces 190 of said slots whereby to cooperate with said screws 182 in holding said plate removably in position. Said plate is also provided with an upstanding projection 192 which engages and constitutes a support for the actuating coil 172 of the electromagnet. Said plate constitutes means to shield the armature-carrying frame from contact with the circuit conductors. When said plate is removed, and the armature is removed from its frame, the actuating coil 172 can be removed from its core and withdrawn through the space between said core and the armature frame.

A relay panel 194 is located in front of the switch and is attached by screws 196 to inwardly extended ears 198 of the side plates 34 and 36. Said panel is composed of insulating material and has upper terminals 198 which are connected by bare strap conductors 200 to the stationary contact members disposed in the rear of the stationary carrier 40. The panel also has lower terminals 202 to which leads of the multi-phase circuit are adapted to be connected.

Suitable switch overload responsive means as the thermal relays 204 are removably received between the terminals 198 and 202 and are adapted to open the switch upon overload by de-energizing the holding coil 172, as is common practice. Said panel is provided with pilot terminals 206 which are adapted to be connected with the control circuits of the switch.

The switch thus described is simple in construction, is made mainly of stamped and molded parts, can be assembled rapidly and can be disassembled without the need of tools other than a screw driver or pliers.

I claim:

1. In an electric switch, stationarily supported contact members, a movable plate having a plurality of movable contact members, a movable supporting frame which supports said plate in horizontal position thereon, and switch operating mechanism arranged to move said frame between switch open and closed position, and said plate being removable horizontally from said frame at will.
2. In an electric switch, the combination of a plurality of stationarily supported contact members, a frame which is movable vertically between switch open and switch closed positions, a contact member supporting plate carried by and movable with said frame, a plurality of contact members carried thereby and movable therewith into and out of engagement with said stationarily supported contact members, said plate being free from positive connection with said frame and adapted to be withdrawn horizontally therefrom with the contact members carried thereby and removed from the switch, and latching means releasably holding said plate in operative position on said frame.
3. In an electric switch, the combination of a plurality of stationarily supported contact members, a frame which is movable between switch open and switch closed positions, a contact member supporting plate carried by and movable with

- said frame, a plurality of contact members carried thereby and movable therewith into and out of engagement with said stationarily supported contact members, said plate being free from positive connection with said frame and adapted to be withdrawn therefrom with the contact members carried thereby and removed from the switch, and means releasably holding said plate in operative position on said frame, arranged to be disconnected from holding engagement with said plate by a force applied in the plane of said plate.
4. In an electric switch, a plurality of stationarily supported contact members, a horizontal frame which is movable vertically toward and away from said contact members, an insulating plate carried by and movable with said frame, a plurality of contact members carried thereby and movable therewith into and out of engagement with said stationarily supported contact members, said plate being free from positive connection with said frame and adapted to be withdrawn therefrom, and having an extended handle by which it can be withdrawn, and said frame having means which guides said plate for movement horizontally off and on said frame.
5. In an electric switch, a movable contact structure including a frame which is movable between switch open and switch closed positions and which has a track provided with an open end, and a contact carrying plate slidably received removably on said track, said plate having contacts on its upper face and having means by which it can be pulled off the open end of said track for the inspection of said contact members and then shoved back in to operative position.
6. In an electric switch, a movable contact structure including a frame which is movable between switch open and switch closed position and has inwardly directed spaced arms providing a track, and a contact supporting plate having opposed grooves in which said arms are received and by which said plate is supported removably on said frame and is slidable along the tracks thereof.
7. In an electric switch, a movable contact structure including a frame which is movable between switch open and switch closed positions and has inwardly-directed spaced arms providing a track, a contact supporting plate having opposed grooves in which said arms are received and by which said plate is supported removably and slidably on said frame, and means releasably securing said plate in operating position on said track.
8. In an electric switch, a movable contact structure including a frame having opposed upstanding side walls provided with spaced inwardly directed parallel arms which constitute a track, an insulating contact supporting plate having opposed parallel grooves in its opposite side faces in which said arms are slidably received and from which said plate can be withdrawn, and means to secure said plate releasably in the aforesaid relation.
9. In an electric switch, a movable contact structure including a frame movable between switch open and switch closed positions having upstanding side walls each of which has a pair of parallel slots therein, and supporting and guiding means for said frame having parallel tracks which are received loosely within said slots and constitute means to guide said frame in parallel lines between switch open and switch closed positions.
10. In an electric switch, a movable contact structure including a contact supporting frame which is movable between switch open and switch closed positions and has opposed upstanding side walls each of which is provided with a pair of parallel slots therein, and supporting and guiding means for said frame including a pair of stationary plates located at said side walls having inturned parallel arms which are received loosely within said slots and constitute tracks which guide said frame by sliding it along said tracks to move in parallel lines between switch open and switch closed positions.
11. In an electric switch, a movable contact supporting structure comprising a frame consisting of a horizontal plate having upwardly reflexed parallel side walls the upper ends of which are reflexed inwardly to provide a pair of spaced horizontal tracks, a movable contact-member supporting plate having parallel grooves in its opposite end faces in which said tracks are located, contact members carried by said plate, said plate adapted to be withdrawn from said frame, removable means securing said plate in its operative position on said frame, said upstanding side walls of said frame each having a pair of parallel vertical grooves therein, and supporting and guiding means for said frame including a pair of stationarily supported plates located at said side walls of said frame and each having a pair of spaced inwardly reflexed arms which are received loosely within said grooves and constitute tracks along which said frame is guided for movement in parallel lines between switch open and switch closed positions.
12. An electric switch having the combination of a stationarily supported horizontal plate, stationarily contact members carried thereby, a vertically movable horizontal plate, movable contact members carried thereby on the upper face thereof, supporting means for said movable contact members including spring supporting pins which extend through said plate and project beyond the bottom face thereof, and a supporting frame which carries said movable plate which is vertically movable toward and away from said stationarily plate and has a bottom wall which underlies said movable plate and is apertured to clear said extended ends of said pins.
13. In an electric switch, stationarily supported contact members, and a movable contact structure including a base, movable contact members carried thereby, a supporting frame which carries said base consisting of a plate which underlies said base and has upstanding side walls which overlie the ends of said base and have removable connections therewith, said plate having downwardly extended ears at its ends adjacent the side walls, and dual switch operating linkages each connected pivotally with a separate one of said ears.
14. An electric switch including a supporting frame having a pair of spaced side plates, an insulating plate overlying the upper ends of said side plate and fixed rigidly thereto, stationary contact members carried on the lower face of said insulating plate, a movable insulating plate located between said side plates and below said stationary plate, movable contact members carried by said movable plate, a movable supporting frame which carries said movable plate, said movable plate having means by which it can be withdrawn horizontally from a supporting relation on said frame in the open position of the switch, and an insulating plate constituting a terminal base secured to the front faces of said

side plates and terminated beneath said movable plate in the switch open position thereof whereby said movable plate can be withdrawn freely above the top of said terminal plate.

- 5 15. An electric switch including a supporting frame having spaced side plates, a stationary insulating plate overlying the top of said side plates and secured rigidly thereto, the lower ends of said side plates having ears which are reflexed toward each other from the front edges of said side plates, an insulating terminal plate fixed rigidly to said ears in spaced relation beneath said stationary contact carrying plate, said side plates

also having at their lower ends other inwardly reflexed ears, and a switch operating electromagnet core disposed between said side plates and fixedly connected with said other ears.

- 5 16. An electric switch having stationary and movable contact members, a movable and removable supporting frame for said movable contact members having a locking recess therein, and a switch frame having a locking projection which is adapted to enter said locking recess in certain 10 positions of said supporting frame and lock it against removal.

GEORGE W. O'KEEFFE.
